[57] **CLAIM**

The ornamental design for a perfume bottle wand, as shown and described.

DESCRIPTION

FIG. 1 is a front elevational view of a perfume bottle wand showing my new design;

FIG. 2 is a right side elevational view thereof;

FIG. 3 is a left side elevational view thereof;

FIG. 4 is a rear elevational view thereof;

FIG. 5 is a front elevational view of a second embodiment of the wand disclosed in FIG. 1;

FIG. 6 is a right side elevational view of FIG. 5;

FIG. 7 is a left side elevational view of FIG. 5;

FIG. 8 is a rear elevational view of FIG. 5;

FIG. 9 is a front elevational view of a third embodiment of the wand disclosed in FIG. 1;

FIG. 10 is a right side elevational view of FIG. 9;

FIG. 11 is a left side elevational view of FIG. 9; and,

FIG. 12 is a rear elevational view of FIG. 9.

The broken line showing of a stopper top is for illustrative purposes only and forms no part of the claimed design.
